UNITED STATES PATENT OFFICE.

WILLIAM F. REACH, OF CHICOPEE, MASSACHUSETTS, ASSIGNOR TO A. G. SPALDING & BROS. MANF'G. COMPANY, OF CHICOPEE, MASSACHUSETTS, A CORPORATION OF MASSACHUSETTS.

THROWING-HAMMER.

1,122,157.

Specification of Letters Patent. Patented Dec. 22, 1914.

Application filed May 25, 1914. Serial No. 840,863.

To all whom it may concern:

Be it known that I, WILLIAM F. REACH, citizen of the United States, residing at Chicopee, Massachusetts, have invented certain new and useful Improvements in Throw-
5 ing-Hammers, of which the following is a specification.

10 My invention is a throwing hammer, used in athletic sports, and it is my aim to construct a hammer with a wear and shock resisting shell with a softer internal filling or body, the filling material being of greater specific gravity than the shell, as in the patent of Murphy 1036138, August 20, 1912, and to further provide a ball bearing connection so as to impart a fast spinning motion to the hammer head as it is thrown around preparatory to hurling, the result being an increased distance of throw.

15 By my invention I secure the benefit of the lead filling of the Murphy patent with the wear resistance shell and the ball bearing connection carried by the shell.

20 In the drawing I have illustrated in the figure a sectional view of the hammer showing also in the figure the full lines and wire handle for spinning the device preparatory to hurling.

25 In the drawing a hollow shell is shown at A, this being made of a shock and wear resisting material, and this casing is filled through the openings a, with a filling of lead or some heavy substance. The casing is provided with an integral core which extends diametrically through the hammer and located within this core is an axle b, screw threaded as at c, at one end and carrying a nut d, the nut being within an enlarged recess in the core which carries the bushing e, and between the inclined face of the bushing and the nut are located anti-friction balls f. There is a like recess at the opposite

end of the core with a like bushing e and ball bearings f, but instead of the nut d the axle is provided with a head g, fitting within the recess and the balls are between the inclined face of the bushing and an inclined shoulder on the head. This head protrudes from the recess and is provided with an eye into which is fitted a wire link h, which supports a handle i. It will be seen that a very simple construction is thus provided, and there is combined the advantages of the Murphy patent referred to as well as the ball bearing feature of the patent of 55 Breakspear Number 649885 of May 15, 1900.

50 My improved construction gives me the benefit of the wear resisting shell while the central core prevents displacement of the interior filling.

55 The openings a are closed by plugs k, and these may be removed to adjust the weight of the lead by subtracting or adding thereto, in case of over or under weight, and thereafter these plugs may be screwed and 60 riveted into place.

65 It will be observed that a very strong construction is provided by the shell and the centrally arranged core.

70 What I claim is:—

A throwing hammer comprising a shock and wear resisting shell having a central core made integral with the shell so as to assure a central position of said core with relation to the shell, the shell having a suitable filling and a handle connected with the core, substantially as described.

75 In testimony whereof I affix my signature in presence of two witnesses.

WILLIAM F. REACH.
